ERNST CURT LOESCHE, OF BERLIN-LANKWITZ, GERMANY

CRUSHING MILL

Application filed April 11, 1928, Serial No. 269,117, and in Germany October 23, 1926.

My invention relates to improvements in crushing mills, and more particularly in mills for crushing coal or similar material comprising a rotary dish or table and rollers bearing thereon. One of the objects of the improvements is to increase the efficiency of mills of this type. I have found that the efficiency of the mill is at its maximum if there is a definite ratio between the diameters 5 of the rolls and the dish, the highest efficiency being obtained, if the said ratio is not more than 1:2, 5.

For further improving the efficiency of the mill the dish is made concave in form, the 10 margin being directed upwardly relatively to the central part along a curve, and the rolls which engage the dish at its upwardly directed concave part are shaped accordingly. Thereby the matter to be ground is exposed 15 to the crushing action of the rolls for a long time. In some cases, and more particularly when grinding tough material, the dish is provided with rings adapted to be placed on the upper margin for enlarging the surface of 20 the dish.

Ordinarily the rolls are disposed on arms 25 rockingly mounted on the frame work of the mill, and they are formed with spherical crushing surfaces corresponding to the surface 30 of the dish. Instead of mounting the rolls in the form of balls loosely engaged by arms holding the same in position and adapted to be rotated by their frictional engagement 35 with the surface of the dish or the material carried thereby. To reduce friction I prefer to provide the said arms with rolls providing an anti-frictional support for the balls.

40 In mills of the class referred to the ground material is delivered from the margin of the dish, and means are provided for producing a blast of air carrying the powdered material away from the dish, the coarser particles 45 falling back into the dish for being again subjected to the grinding action of the rolls. The blast of air is supplied to the casing of the mill below the rotary dish, and it is directed upwardly therefrom and around the 50 circumference of the dish. I have found that

the efficiency of the mill is improved if the cross-sectional area of the passage of the air flowing from the bottom side of the dish upwardly remains substantially constant. The 55 said passage is provided by the annular space provided below and around the dish, the air being supplied substantially at the middle of the said annular space. Therefore, the circumferential dimension of the annular passage is gradually increased from the center 60 of the dish to the upper circumference thereof, and in order to have a passage of substantially uniform cross-sectional area it is necessary to reduce the radial dimension 65 of the annular passage from the center to the circumference of the dish at the rate of the increase of the circumferential dimension. I have found that when thus constructing the annular passage the blast 70 of air which is ordinarily delivered into the said passage in tangential direction is adapted to keep the passage clear even of coarse material, the blast of air carrying the said coarse material falling from the margin of 75 the dish upwardly and returning the same into the dish or into a shifting apparatus provided above the dish.

In mills of the class referred to it is frequently desirable to examine the rolls and the bearings thereof. Another object of the 80 improvements is to provide a mill in which the rolls can be readily removed from the casing enclosing the rotary dish and the rolls without special machinery, and with this object in view my invention consists in so combining the rolls and their bearings with lids for closing holes made in the casing of the mill, that the rolls can be rocked out of the 85 casing through the said holes while simultaneously removing the lids.

90 Particularly in case of heavy mills it is objectionable that the rolls are liable to roll directly on the surface of the dish without material to be crushed being interposed 95 between the same and the dish. Therefore, in order to prevent direct contact between the rolls and the surface of the dish I provide stop members adapted to hold the rolls a certain distance away from the surface of the 100 dish.

dish. Preferably, the said stop members are adjustable.

Other objects of the improvements will appear from the following description.

5 For the purpose of explaining the invention several examples embodying the same have been shown in the accompanying drawings, in which the same letters of reference have been used in all the views to indicate 10 corresponding parts. In said drawings,

Fig. 1 is a sectional elevation showing the mill,

Fig. 2 is a sectional plan view taken on the line 2—2 of Fig. 1,

15 Fig. 3 is a detail sectional elevation showing a modification of the means for supplying the material to the mill,

Fig. 4 is a sectional elevation showing a modification of the rotary dish or table and 20 a crushing ball cooperating therewith,

Fig. 5 is a top plan view of Fig. 4,

Fig. 6 is a sectional elevation showing another modification of the rotary dish or table,

25 Fig. 7 is a detail sectional elevation showing a modification of the means for enlarging the active surface of the dish.

Fig. 8 is a sectional elevation of a part of the casing of the mill, a rotary table or dish, and a rockably mounted crushing roll,

30 Fig. 9 is a sectional elevation showing a modification of the construction of the crushing roll and the supporting means therefor,

Fig. 10 is a detail sectional elevation looking from the left of Fig. 9 and showing the 35 manner of mounting the crushing roll on the lid, and

Fig. 11 is a sectional elevation showing another modification of the mill.

40 In the example shown in Fig. 1 the mill comprises a casing having a bottom part 1, a concave part 2 and a cylindrical top part 3, the bottom part 1 comprising a base plate 4 and a partition 5. In bearings 6 and 7 provided in the base plate 4 and the partition 5 a vertical shaft 8 is mounted which is adapted to be rotated by means of a bevel gearing 9 keyed to a shaft 10 and a pulley 10'. To the top part of the shaft 8 a table or dish 11 is secured which is curved upwardly at its margin thus providing a concave top face. The 45 top face of the dish 11 is engaged by one or more rolls 12 bearing on the concave marginal part of the dish 11 and having a configuration corresponding to the said concave part. Each of the rolls 12 is rotatably mounted on an arm 13 rockingly mounted at 14 on a member 15 rockingly mounted on a lug 16 formed on the part 2 of the casing of the machine, and the member 15

50 is fixed to or made integral with a lid 17 closing an opening 18 made in the wall of the top part 3 of the casing, the dimension of the said opening 18 being such that the roll 12 can be rocked out of the casing. The arm 13 is formed with an extension 19 formed with

a hole, and through the said hole a rod 20 fixed to the arm 15 is passed. To the screw-threaded outer end of the said rod 20 a nut 21 is screwed which provides a support for a coiled spring 22 bearing on the extension 19 of the arm 13 and tending to force the roll 12 towards the dish 11. One or two nuts 23 are provided on the bolt 20 at the side of the extention 19 opposite to the spring 22, and the said nuts are adjustable on the 75 bolt. The nuts 23 provide an abutment for the arm 13 for limiting the movement of the roll 12 towards the dish 11. Thus the nuts can be set in position for holding the roll 12 a suitable distance away from the surface 80 of the dish 11 for preventing direct contact of the rolls and the surface of the dish 11.

There is only one roll shown in the drawings for the purpose of clearness, but preferably several rolls are used.

85 The material to be ground is supplied to the casing through a pipe 25 including a feeding member in the form of a rotary wheel 26 having radial arms 27, the material being fed through the said pipe to the part of the casing below the dish 11 and being carried upwardly by a blast of air.

90 The said blast of air is supplied through a pipe 30 opening tangentially into the part 2 of the casing below the dish 11. Thus the 95 blast of air is whirled around within the space provided between the bottom part of the dish 11 and the wall of the part 2 of the casing and it rises upwardly from the said chamber into the part 3 of the casing, from whence it escapes through a tubular outlet 31. I have found that the efficiency of the blast of air is particularly high if the cross-sectional area of the passage 32 remains constant from its bottom or central part to its top or circumferential part. Therefore the radial dimension of the said chamber is gradually reduced from its bottom part to its top part. If the radius of the annular passage at the top part is r^1 and at another part r^2 and the breadth 100 of the passage at the said points is respectively x^1 and x^2 , the circumferential areas are at the ratio $r^1 : r^2$. Therefore, in order to have uniform cross-sectional areas throughout the length of the passage, the breadth of the passage must be reduced from the bottom part to the top part according to the proportion 105 $r^1 : r^2 = x^2 : x^1$.

110 In the operation of the apparatus the blast of air rising from the passage 32 carries away the powdered material through the outlet 31. In constructions now in use the blast of air produces whirls on the central and top part of the dish, so that the material being crushed is liable to be carried away. Therefore, in 115 order to prevent the action of the blast of air on the material being crushed provision is made for causing the blast of air to flow alongside the circumferential wall of the part 3 of the casing. In the example shown in 120 125 130

Fig. 1 the said means are in the form of a cylinder 35 and disposed concentrically within the top part 3 of the casing, the said cylinder being suspended for example from the top wall of the part 3. Above the said cylinder there is a ring of vertical vanes 36 disposed radially or preferably at suitable angles to the radius of the casing. The top wall 37 of the cylinder is in the form of a funnel having rockable gates 38. The inner diameter of the part 3 of the casing is equal to or smaller than the diameter of the top part of the dish.

In the operation of the mill the material to be ground, for example coal, is supplied to the dish 11, which is rapidly rotated. Therefore the rolls 12 crush the coal which gradually rises from the center of the dish to the circumference from whence it is thrown outwardly by centrifugal action. Through the pipe 30 a blast of air is admitted to the annular passage 32, which blast of air rises upwardly around the circumference of the dish and carries away the ground material delivered from the dish. The heavy particles which have not been sufficiently ground fall back into the dish 11, while the finer particles are carried upwardly by the blast of air and through the annular passage 39 provided between the cylinder 35 and the wall of the part 3 of the casing. Thus the blast of air moves upwardly along the wall of the casing, and it has no objectionable action on the material being ground. The separation of the coarser particles of the material is assisted by the tapering form of the bottom part of the wall of the casing 3, by which an inward direction is imparted to the said particles. The fine particles of the material are carried upwardly and deflected inwardly and through the passages provided between the vanes 36. By the said deflection a further separation of coarse particles is accomplished. By reason of the inclined position of the vanes 36 the blast of air is delivered into the cylinder in tangential direction, so that the separation of the coarser particles is continued by centrifugal action, the air and finest particles of the material being delivered through the outlet 31, while the separated particles fall into the funnel 37 from which they are intermittently removed after opening the gates 38. The material delivered from the funnel 37 falls on the dish 11 for being again ground.

If it is desired to examine the rolls 12 the rockable lids 17 are rocked outwardly together with the rolls 12.

The diameters of the rolls 12 and the dish 11 are at the ratio of 1:2, 5 or less. I have found that thereby the efficiency of the mill is at its maximum.

In Fig. 3 I have shown a modification of the means of supplying the material to the rotary dish 11. As shown, the said dish is in the form of a funnel or chute 251 ending at a part above the dish 11, so that the ma-

terial to be crushed is directly supplied to the top face of the said dish.

In Figs. 4 and 5 I have illustrated a modification of the rolls. As shown in the said figures the rolls are in the form of balls 40 loosely rolling on the top face of the dish 11. For holding the balls in position when rotating the dish 11, arms 41 are fixed to the wall of the casing 3, which arms are preferably provided with anti-friction rollers 42 located in position for engaging the balls 40.

For grinding very tough material I extend the dish 11 at its upper margins by placing thereon one or more rings 44, as is shown in Fig. 6. In the modification shown in Fig. 7 a single ring 441 is provided, which is fixed to the circumferential face of the dish 11 by means of screws 442 passed through vertical slots 443. By reason of the said slots the ring 441 can be set in different positions vertically for more or less enlarging the active surface of the dish 11.

In Fig. 8 I have shown a modification in which the arms 45 on which the rolls 46 are rotatable are made integral with arms 47 rockingly mounted on lugs 48 provided on the casing of the apparatus. To the lid 49 a bolt 50 is secured which is passed through a bore of the arm 47 and carries at its outer end a disk 51 and a nut 52 providing a support for a coiled spring 53 acting on the arm 47 and tending to push the roll 46 towards the surface of the dish 11. For examining the roll 46 the whole system including the arm 47, the lid 49 and the roll 46 is rocked outwardly into the position shown in dotted lines.

The means for arresting the roll 12 in a position away from the surface of the dish 11 and consisting in the example illustrated in Fig. 1 of the nuts 23 may also be provided in other mills in which the rolls are forced in contact with the dish by centrifugal force, in which case bails may be provided for holding the rolls away from the surface of the dish.

In the modification shown in Figs. 9 and 10 the lid 70 is fixed to the casing 71 of the mill by means of screws 72, and it has a pivot bolt 73 fixed thereto, which provides a bearing for the arm 74 carrying the crushing roller 75. At its rear end the arm 74 is formed with a hole through which a bolt 76 carrying a nut 77 is passed, the said bolt being jointed to the lid 70 at 78. Between the rear end of the arm 74 and the nut 77 a coiled spring 79 is placed on the bolt 76, which spring tends to force the crushing roll 75 on the dish 11. For removing the roll 75 from the mill the screws 72 are unscrewed, whereupon the lid and the roll are simultaneously removed from the mill.

In the examples so far described the material delivered from the dish 11 is carried upwardly by the blast of air, so that special

means for removing the material from the passage 32 may be dispensed with. In Fig. 11 I have shown a modification in which mechanical means are provided for removing the material falling from the dish downwardly and returning the same on the dish. The dish 55 is mounted substantially in the same way as has been described with reference to Figs. 1 and 2. The blast of air is delivered into the casing 56 through an annular passage 57. Between the circumference of the dish 55 and the wall of the casing 56 a comparatively broad annular passage 58 is provided, so that the blast of air rising from the said passage is comparatively weak, which may be desirable in some cases for having a good sifting action. Thus a part of the coarse material may fall into the said annular chamber, and in order to remove the material from the bottom of the said chamber I provide the dish 55 at its circumference with one or more buckets 59 adapted to collect the material from the bottom and to throw the same upwardly and against the tapering wall of the casing 56. Thus the material is again thrown into the blast of air and the fine particles are carried away by the said blast, while the coarser particles, which are directed inwardly by the tapering wall of the casing 56 and the direction of the blast of air are returned on the dish 55.

The construction of the rolls 60 may be the same as that described with reference to Fig. 1. But as shown, they are not constructed for being rocked outwardly, but they are rockingly mounted on lugs 61 rising from the wall of the casing 56, springs 62 being provided for forcing the roll 60 on the surface of the dish 55.

40 I claim:

A mill, comprising a casing having an opening, a removable lid for closing said casing, a dish rotatable around a vertical axis and mounted within said casing, a crushing roll bearing on said dish and a rockably mounted arm on which said roll is mounted and extending through said hole into said casing and forming a unit with each single lid, said roll and lid being mounted for being removed from the casing as a unit.

45 In testimony whereof I have affixed my signature.

50 ERNST CURT LOESCHE.
